INSERTS FOR ROCK DRILL BITS

Helmuth H. Schlossin, Johannesburg, Transvaal, Republic of South Africa, assignor to Hard Metals Limited, Nuffield Township, Springs, Transvaal, Republic of South Africa

Filed Dec. 19, 1962, Ser. No. 245,914

Claims priority, application Republic of South Africa

July 2, 1959

4 Claims. (Cl. 175—410)

This invention relates to rock drill bits of the kind including a chisel-shaped insert of hard metal secured within a slot in the bit. The main accent of the invention is on bits having a single insert (integral or built-up), but it is also applicable to bits having inserts spaced in cruciform formation or any formation with more than one cutting insert.

The present application is a continuation-in-part of application No. 32,940 filed on May 31, 1960, and abandoned on the filing of the present application.

With the advent of cemented tungsten carbide (usually known as hard metal) percussive rock drilling has been improved beyond recognition. However, hard metal is an expensive material and the aim of manufacturers is to increase the utility of the material. It is believed that the optimum in relation to the composition of hard metals has almost been reached.

In regard to the shape of the cemented tungsten carbide bits a lot of work has been done, but over many years shape has been more or less standardized as that shown in FIGURE 1. The standard shape is a chisel shape which has been used also for steel drilling edges.

Applicant is aware of the fact that a departure from the standard shape has been proposed in the prior art. In the latter case it was proposed that cutting wings have flattened forward faces or in other words the cutting edges progressively broadened from the centre towards the reaming ends. The greater amount of material present at the outer ends of the wings where abrasion is greatest due to the greater volume broken per revolution is said to make the bit more durable. Applicant has tested the teaching of this prior art on tungsten carbide inserts and has found that greater durability as compared to a standard chisel-shape in fact results.

The present invention is based on the unexpected discovery that durability may be increased still further if the cutting edge is flanked by concave lands arranged to intersect (the cutting edge being the intersecting line) a distance of preferably at least 0.019 inch below the

2

top of the insert. Coupled with increased durability is an increase in penetration speed.

The invention is further discussed with reference to the accompanying drawings, in which

FIGURE 1 is a side elevation of a standard insert;

FIGURE 2 is a side elevation of an insert according to the teachings of the prior art;

FIGURE 3 is a section on the line 2—2 of FIGURE 2;

FIGURE 4 is a plan view of FIGURE 1;

FIGURE 5 is a side elevation of one embodiment of the invention;

FIGURE 6 is a section on the line 5—5 of FIGURE 5;

FIGURE 7 is a plan view of FIGURE 4;

FIGURE 8 is a side elevation of the preferred embodiment;

FIGURE 9 is a section on the line 8—8 of FIGURE 8; and

FIGURE 10 is a plan view of FIGURE 7.

20 In FIGURES 2 to 10 similar parts have been designated by the same reference numbers. Thus in each case there is a substantially rectangular prismatic body 10 with reaming ends 11 which are curved about the centre of the insert and inclined towards the base 12 in a well known manner.

Each insert has a cutting end comprising a cutting edge 13, snubs 14 to either end of the edge 13, substantially triangular faces 15 with their apices at the cutting edge and broadening towards and into the snubs 14 and 30 lands 16 flanking the cutting edge 13.

In each case also the lands 16 are concave as can be seen from the drawings.

In FIGURES 2 to 4, the faces 15 constitute a progressive broadening of the edge 13 towards the reaming 35 ends 11. As seen from FIGURE 4, the cutting edge and the faces 15 are in the same plane. The cutting edge is, therefore, a straight line flanked by triangular flats.

In the embodiments of FIGURES 5 to 7 and 8 to 10 40 the cutting edge 13 is concave below shoulders 18 at the junctions of the faces 15 and the snubs 14. In each case the insert is 1.441 inches wide (at its maximum width), 0.398 inch thick and 0.625 inch high. The main difference lies in the depth of the concavity of the cutting edge below the shoulders 18. In the case of the embodiment of FIGURES 5 to 7 it is 0.019 inch and in the case of preferred embodiment 0.059 inch. With wider bits a depth of 0.080 inch has given good 45 results.

In practice (when drilling quartzite), it is found that the construction of FIGURES 2 to 4 (called "Flat Top") gives improved results particularly in speed of penetration over the standard bit of FIGURE 1. The embodiment of FIGURES 5 to 7 (called "Shallow Saddle") gives better results while the best results are achieved with the preferred embodiment of FIGURES 8 to 10 (called "Deep Saddle").

The results on which the observations in the previous paragraph are based are tabulated in Table I:

In Table I "gauge loss" has been chosen as a measure of durability. A small gauge loss means good durability. Gauge loss is the amount by which the overall distance between the reaming ends 11 is decreased. Cumulative figures have been given in Table I. After the first three feet or after the first hole the gauge loss was 0.03 mm. in three cases and 0.02 mm. in the case of the deep saddle and so on. In the tests which led to Table I there was no resharpening and, as can be seen, fifteen holes were drilled in each case.

The hole depth in each case was 3'0".

The term "penetration speed" as used in Table I means the number of inches that the bit penetrated per minute of drilling time.

The values are averages of inserts of each type that were used in the tests.

As to durability the figures clearly show that the embodiments of the invention have an advantage over the standard and the flat top. The same applies to penetration speed.

In another test the standard and the deep saddle were run against each other to the end of their respective useful lives. The results are tabulated below in Table II.

Table II

Hole.....	1	15*	16	30*	31	45*	46	60*	61	75*	76	90*	91	105
Penetration speed, ins./min.:														
Standard.....	7.7	7.1	9.0	7.4	8.8	7.0	9.4	7.0	9.3	8.2	9.7

*Resharpened after this hole.

In Table II the depth of each hole was 3'6" and the average life of five bits of each type is given. The drills were carefully resharpened at the end of every 15th hole that was drilled.

In the case of Table II durability was measured by means of "wear resistance." Wear resistance is the number of feet drilled by an insert divided by the number of millimetres by which its length has decreased as a result of such drilling and the necessary resharpening, which as shown was after each fifteenth hole. The figures are therefore for the first hole drilled by a new bit, the hole just before resharpening and the hole immediately following resharpening and so on before and after each

resharpening. Wear resistance is calculated by multiplying the number of holes drilled with 3.5 feet and dividing that by the overall decrease in length.

As pointed out above a reason why the flat top should give better results than the standard bit is given in the prior art. However, there is no apparent reason why the teachings of the present invention should provide any advantages over the flat top. This much is clear: the advantages do exist. In the course of actual drilling on the South African gold mines with drills equipped with the deep saddle a practical problem was encountered as a result of these improved results. It was found that higher water pressures were needed to carry away the cuttings that were formed with the deep saddle to prevent the drill from sticking in the hole.

15 I claim:

1. An insert for a percussive rock drill bit comprising an elongated substantially rectangular prismatic configuration and having a flat base; two opposed flat sides at right angles to the base; two opposed substantially parallel reaming ends at right angles to the base and the long axis of the insert; and a substantially chisel-shaped cutting formation opposed to the base, the cutting formation consisting in inclined concave lands meeting at a short axis of the insert and intersecting the flat sides, a concave cutting edge being formed where the concave lands meet and such cutting edge broadening into a pair of divergent triangular faces continuous with and having the same concavity as the cutting edge, and a pair of inclined snubs joining the bases of the triangular faces with the reaming ends, a shoulder being formed by the base of each of the triangular faces merging with the uppermost portion of each snub.

30

2. The insert claimed in claim 1 in which the lands meet at least 0.019 inch below the shoulders.

3. The insert claimed in claim 1 in which the lands meet at between 0.019 inch and 0.080 inch below the shoulders.

4. The insert claimed in claim 3 in which the lands meet at 0.059 inch below the shoulders.
